UNITED STATES PATENT OFFICE.

WILLIAM GRAHAM MOSIER, OF GREENVILLE, MISSISSIPPI.

RAZOR-STROP.

SPECIFICATION forming part of Letters Patent No. 678,676, dated July 16, 1901.

Application filed January 18, 1901. Serial No. 43,739. (No model.)

To all whom it may concern:

Be it known that I, WILLIAM GRAHAM MOSIER, a citizen of the United States, and a resident of Greenville, in the county of Washington and State of Mississippi, have invented a new and Improved Razor-Strop, of which the following is a full, clear, and exact description.

This invention relates to certain devices for holding razor-strops by means of which a plurality of strops may be held, so that when one strop is in use the others will not interfere with the operation of stropping the razor and so that the strops may be turned readily from side to side, so that the razor may be applied to either face, as desired.

This specification is a specific description of one form of the invention, while the claims are definitions of the actual scope thereof.

Reference is to be had to the accompanying drawings, forming a part of this specification, in which similar characters of reference indicate corresponding parts in all the views.

Figure 1 is a side elevation of the invention in the position of rest. Fig. 2 is an enlarged sectional view showing one strop in use and illustrating the position in which the other strop would hang if not grasped by the operator, and Fig. 3 is an enlarged sectional plan view of the invention.

a and *a'* represent the two strops. These strops are engaged with bails *b*, having one side *b'* provided with a hook releasably engaging the part of the bail which holds the strop, so that by disengaging the hook *b'* the strop may be removed from the bail and a second strop engaged therewith. This permits the various strops to be interchanged at will. Each bail *b* is provided with a swivel *c*, which swivels are engaged, respectively, in approximately U-shaped yokes *d*. The swivels *c* are engaged with the yoke so that the swivels may turn freely therein, and this permits the strops to be turned into any position desired in the manner indicated by full and dotted lines in the lower part of Fig. 2. The yokes *d* are fitted one within the other and are pivotally mounted on trunnions *e'*, formed on a box *e*, which lies between the arms of the inner yoke. Each yoke is cut away at its free portion, as indicated at *d'*, thus permitting

the yokes to move completely the one within the other, so that when the device is at rest the two strops *a* may lie closely together. This arrangement also enables the two strops 55 to be held together during the use of the device. With barbers it is frequently the custom to hold two or more strops together when sharpening a razor, so as to give additional stiffness to the sharpening-surface. This is 60 therefore possible with my invention.

In Fig. 2 I have shown only one strop held in position for operation; but it is clear that both strops may be grasped and held side by side during the sharpening. The box *e* carries a rod *f*, which is loosely fitted therein, so as to turn freely, and this rod *f* is adapted to be connected with the wall or other support through the medium, for example, of a screw-eye *g*. From this construction it follows that 65 not only may the strops be turned from side to side, but the whole device may be turned freely around the rod *f*. The structure of the box *e* not only allows this movement, but it further allows the independent swinging 70 movement of the box *e*.

Having thus described my invention, I claim as new and desire to secure by Letters Patent—

1. The combination with a razor-strop of a 80 bail engaged therewith, a swivel attached to the bail, a pivotally-mounted yoke with which the swivel is engaged, and means for suspending the yoke.

2. The combination of two yokes capable of 85 independent pivotal movement toward and from each other, and devices attached to the yokes for respectively engaging the razor-strops.

3. The combination of two yokes capable of 90 pivotal movement independently toward and from each other, means for supporting each yoke to turn bodily around a longitudinal axis, and devices engaged with the yokes and comprising each a swivel, said devices being 95 adapted for engagement with a razor-strop.

4. The combination of devices each adapted to engage a razor-strop, and comprising a swivel, a yoke with which each swivel is connected, a box having trunnions on which the 100 yokes are pivotally mounted, and a rod fitted loosely in the box.

5. The combination of two yokes fitted one within the other and capable of pivotal movement toward and from each other, the yokes being cut away at their free ends to permit the movement of the yokes closely together, and devices engaged with each yoke respectively for connecting razor-strops therewith.

In testimony whereof I have signed my name to this specification in the presence of two subscribing witnesses.

WILLIAM GRAHAM MOSIER.
